UNITED STATES PATENT OFFICE

LEONARD D. STEPHENSON, OF ASHLAND, OREGON

AMALGAMATOR

Application filed April 13, 1928. Serial No. 269,786.

My invention relates to amalgamators for recovering gold and silver from mill or placer tailings and the like wherein charges of slimes are circulated from a tank through a casing and agitated with mercury held suspended in the circulating slimes, the slimes being returned to the tank over amalgamating plates, and suitable reagents being introduced for cleansing the metals and accelerating the action of the mercury thereon when necessary.

The primary object of my invention is to provide an improved method and machine for amalgamating gold and silver.

Another very important object is to provide an improved machine for treating gold and silver bearing slimes and the like to obtain an efficient amalgamation and a substantially complete recovery.

A further object is to provide an improved machine which will increase the efficiency and the percentage of recovery.

Another object is to provide an improved machine whereby tailings and slimes from ores of various characters may be effectively treated with reagents suited to render the gold or silver content readily amenable to the action of mercury and to insure an intimate association of mercury with every particle of precious metal whereby a substantially complete recovery may be obtained.

A further object is to provide an improved machine whereby the material to be treated may be subjected to a maximum exposure to mercury with a minimum expenditure of power and time.

A further object is to provide an improved machine which may be easily charged and emptied, and in which the material to be treated may be readily thinned with water to the desired consistency.

Another object is to provide an improved machine whereby air may be introduced to aerate the product being treated.

Another object is to provide an improved machine which will minimize loss of mercury and amalgam.

A further object is to provide an improved machine which will facilitate the collecting of mercury and amalgam therefrom, and also

facilitate the restarting of the machine after a clean-up.

A further object is to provide an improved machine which may be readily adjusted for the treatment of various kinds of materials to vary the circulation and agitation of the material as required.

A still further object is to provide an improved machine of simple and efficient construction which can be manufactured and operated economically and in which no part is subjected to heavy wear necessitating repair or replacement.

I accomplish these and other objects by means of the improved device disclosed in the drawings forming a part of the present application wherein like characters of reference are used to designate similar parts throughout the specification and drawings, and in which—

Fig. 1 is a vertical mid-section of my improved amalgamator;

Fig. 2 is a plan view of the amalgamator, portions being broken away in successive planes to disclose the construction and arrangement of parts;

Fig. 3 is a horizontal section taken upon the line 3—3 of Fig. 1 in the direction indicated; and

Fig. 4 is a broken plan view of the aerating connection.

Referring to the drawings, the numeral 1 is used to designate in general a tank or receiver arranged to receive a charge of tailings, slimes, or other material to be subjected to treatment for removing precious metals therefrom by amalgamation. The tank 1 is provided with an inlet 2, preferably arranged at an angle and opening into a side of the tank 1, said inlet being connected to a suitable hopper or other device, not shown, from which a measured charge of slimes, or the like, is delivered into the tank. An outlet connection 3 provided with a suitable valve 4 is connected into the tank at a point slightly above the bottom thereof. A water connection 6 is connected into the inlet 2 and arranged to deliver water into said inlet while a charge is being delivered into the tank to reduce said charge to a desired consistency.

100

The bottom of the tank is constructed to incline from all directions to the center of the bottom to form a well to receive a suitable charge of mercury 7.

5 A casing designated in general by the numeral 8 is mounted within the tank 1. The casing 8 rests upon a plurality of supporting lugs 9 formed within the bottom of the tank 1, the lower edges of the casing being preferably curved slightly inwardly and being supported directly over the mercury well and slightly above the upper surface of the mercury 7. The upper end of the casing extends above the top of the tank 1 and is provided 10 with a reduced portion 11. The casing is held in axial relation to the tank by means of a plurality of adjusting screws 12 threaded through the sides of the tank 1 and engaging the sides of the casing whereby the casing may 15 be adjusted and held in true axial position.

An amalgamating tray 14 is secured upon the top of the tank 1. The tray 14 is preferably constructed with a downwardly disposed flange 16 fitting around the upper end of the tank and held in engagement therewith by a plurality of screws or other securing members 17. The bottom of the tray slopes from all directions toward a central opening through which the upper reduced end of the 20 casing 8 extends, the edges of the opening being spaced from the casing to provide a passage from the tray into the top of the tank. The tray is made of relatively wide diameter and the outer edge is provided with an upwardly disposed flange 18. The bottom of the tray is lined with amalgamating plates 19, preferably formed in sectors fitted neatly into the bottom of the tray. The plates 19 are surfaced with mercury in the well known 25 manner and are constructed and matched so as to provide an evenly sloping surface over which the slimes may flow back into the tank as hereinafter more fully explained.

An amalgamating member designated in general by the numeral 21 is mounted upon the top of the casing 8. The member 21 consists preferably of a body having a downwardly disposed flange 22 forming a seat arranged to rest upon the top of the casing 8, said body extending outwardly and sloping downwardly toward the outer flanged edge of the tray 14. The member 21 is provided upon its upper surface with amalgamating plates 23 surfaced with mercury in the ordinary manner and preferably constructed as sectors fitted neatly together and providing an outwardly draining surface. The outer edge of the member 21 is provided with a cupped edge 24 arranged 50 to retain a supply of mercury 26, the extreme outer edge being spaced from the bottom and outer flange of the tray 14 to permit slimes to flow from the member 21 onto the tray and thence to the tank 1.

55 A distributing member 27 is mounted above

the member 21, said member 27 preferably being mounted by means of a downwardly disposed flange 28 seating within an annular groove 29 formed in the top of an annular flange portion 31 formed upon the member 21 and extending upwardly from the top of the casing 8 as a continuation thereof. The distributing member slopes outwardly substantially parallel to the surface of the member 21 and spaced slightly above said surface. The outer edge of the member 27 is upwardly curved as at 32 to provide a slime retaining rim, and a plurality of apertures 33 are formed at regular intervals over substantially the entire area of the bottom of the member 27.

A shaft 34 is mounted axially within the casing 8, the lower end resting upon the pointed end of a plug 36 threaded into the bottom of the tank 1 and forming a take-up bearing for said lower end of the shaft. The upper end of the shaft is engaged by a relatively long bearing 37 formed upon a spider 38, the legs of which extend radially to points above the edges of the tray 14 above which the spider is secured and supported by means of bolts 39 extending through the ends of the legs of the spider and through openings formed in an outwardly disposed flange 41 formed around the top of the flange 18, tubular spacers 42 being mounted upon the bolts between the spider and the flange 41. The shaft 34 is provided with a bevel gear 43 meshing with a driving gear 44 secured upon a shaft 46 driven in any suitable manner from a source of power, not shown. The thrust upon the shaft 34 is carried by a collar 47 secured upon the shaft immediately above the bearing 37.

The shaft 34 is provided with a long key-way 48. An impeller 49 is keyed onto the lower end of the shaft at a point slightly above the lower edge of the casing 8, said impeller being provided with upwardly faced impeller blades 49'. An agitator 51 is keyed onto the shaft 34 at a point between the impeller 49 and the top of the casing 8, said agitator preferably consisting of a hub provided with a pair of diametrically opposite paddles 51' having substantially vertical paddle surfaces. The long key-way 48 permits both the impeller and the agitator to be adjusted vertically along the shaft.

A manifold 52 is mounted in any suitable manner just below the bottom of the tank 1, said manifold being provided with a plurality of tubular members 53 extending upwardly into the tank and having their inner ends curved to open downwardly substantially as shown. The manifold is connected to a source of air pressure, not shown, in any convenient manner, whereby air may be introduced into the bottom of the tank if desired.

In operation, my improved amalgamator is

mounted independently, or in a battery with a plurality of machines, preferably by means of shiftable timbers 54 supporting the tank 1 by means of supporting lugs or flanges 56 formed on the outer surface of the tank. In 5 starting the machine, the plates 19 and 23 are freshly surfaced with mercury in the well known manner, and a supply of mercury is placed in the well formed at the bottom of the tank 1 and in the cupped edge 24. A charge 10 of finely ground pulp or slimes such as mill or placer tailings, or other gold or silver bearing material, is introduced through the inlet 2 into the tank. Such pulp is accompanied with sufficient water to run freely through the 15 inlet 2, and sufficient additional water is introduced with said pulp or slimes through the water connection 6 to reduce the consistency to the desired degree. The tank is filled to approximately the level indicated by the 20 heavy dotted line X. Power is then applied to rotate the shaft 34 and thereby actuate the impeller 49 and the agitator 51, the shaft being started either while the charge is being introduced or before the pulp has time to settle 25 from the water introduced therewith. As the impeller is actuated a current is created upwardly within the casing 8. As the rotation of the impeller is continued rapidly, the 30 slimes are forced upwardly through the casing and a suction is created at the bottom of the casing, additional quantities of the slimes being drawn into the bottom of the casing and the level of the slimes within the casing 35 gradually raised until the slimes overflow from the top of the casing into the distributing member 27, the level outside of the casing being lowered to a plane at approximately the level indicated by the light broken line Y. 40 The overflowing slimes flow outwardly over the upper surface of the distributing member and through the apertures 33 therein whereby the overflowing slimes are distributed substantially uniformly over the entire 45 upper surface of the plates 23 of the amalgamating member 21. The slimes flow outwardly over the mercury contained in the cupped edges 24 of the amalgamating member and into the outer edges of the tray 14, 50 and thence flow downwardly over the amalgamating plates 19 and back into the tank through the opening around the casing 8. The continued rotation of the impeller maintains a steady circulation of the slimes where- 55 by the slimes are caused to be circulated past the mercury at 7 and 26, and to be spread and flow in a thin sheet over the amalgamating plates 19 and 23, thereby exposing the slimes to a large surface area of mercury. 60 The suction generated by the impeller at the bottom of the casing 8 causes small globules of the mercury at 7 to be lifted and carried upwardly with the upwardly circulating slimes. The globules are lifted to a height 65 proportional to the speed of the impeller and

the distance said impeller is positioned from the bottom of the impeller. By a proper regulation of the speed and elevation of the impeller these globules of mercury may be lifted to a desired elevation within the casing 8 70 without permitting any appreciable quantity to be carried over the top of the casing with the overflowing slimes, the globules being held suspended in the circulating slimes and being whirled rapidly about the casing with 75 the current of slimes. The whirling globules of mercury, scattered throughout the casing, cause the mercury to come into contact with substantially every particle of the solid elements of the slimes. The paddles 51', 80 rotating with the shaft 34, agitate the passing stream of slimes and break up the smoothly whirling stream and scatter the globules of mercury throughout the upper portion of the casing and prevent the globules from segregating around the sides of the casing due to 85 centrifugal force. The globules of mercury present a large surface area of mercury which is kept constantly in contact with portions of the slimes, thereby subjecting said slimes 90 to a substantially continuous exposure to the mercury and effecting a rapid and efficient extraction of the gold and silver.

After the charge has been circulated for a sufficient time to insure a complete extraction of the precious metals, the impeller is stopped and the slimes allowed to drain back to normal starting level upon the inner and outer sides of the casing. The mercury suspended within the casing settles rapidly to 95 the bottom of the tank and unites with the mercury in the well at 7. After the mercury has settled, the outlet valve 4 is opened and the slimes are drawn off through the outlet 3. After the tank has been drained, the valve 4 is again closed and a fresh charge of slimes 100 introduced and treated as above described.

The rapid whirling and continued circulation of the slimes within the casing effectively exposes all particles of the slimes 110 to the action of the mercury and in most cases effects substantially a complete recovery within a relatively short time. In some cases, the gold or silver exists in a condition such that the amalgamation is not efficient. In 115 the treatment of slimes in which this condition exists, a suitable reagent is introduced into the tank to cleanse or otherwise render the gold or silver amenable to amalgamation. Thus, in treating slimes from certain 120 types of ores, it is desirable, and sometimes necessary, to add proper quantities of salt, copper sulphate, potash or other reagents. The use of such reagents must of course be determined by the character of the particu- 125 lar product to be treated. Thus in some cases, an oxidizing agent must be used, while in others a reducing agent is necessary. In some cases a dilute acid is found desirable, while in other cases, as in the treatment of greasy 130

talc tailings and the like, an alkali must be added. In any case, the reagent desired is added directly to the contents of the tank, the subsequent circulating and agitating to which the slimes are subjected causes the reagent to be rapidly and uniformly distributed throughout the charge and each particle of the slimes will be subjected to the action of such reagent and rendered amenable to amalgamation when again exposed to mercury while being circulated through the machine, thereby permitting a substantially complete recovery to be made even from the most obdurate ores.

In the treatment of many kinds of products, it has been found that by introducing air into the circulating mixture a more rapid and efficient amalgamation is effected. In treating such products, air is introduced through the tubular member 53 from the manifold 52. The air enters immediately below the open lower end of the casing and serves to aerate the entire charge of slimes. The inner ends of the members 53 are turned downwardly to prevent mercury or amalgam from settling into the tubular members and being lost.

The mercury and amalgam is removed from the well at the bottom of the tank periodically. This is accomplished by unscrewing the plug 36 which is tapped into the center of the depression at the bottom of the tank. The plug is preferably provided with a lever 58 pivotally connected thereto whereby the plug may be unscrewed and replaced. The lever is normally locked into engagement with a lug 57 upon the bottom of the tank to guard against unauthorized removal of amalgam. When the plug is removed the mercury is drained into a suitable receptacle and subjected to the ordinary treatment for separating the gold and silver. The plug is then returned and fresh mercury substituted.

A complete clean-up is made periodically. At such times the bottom of the tank is completely cleaned, and the mercury and amalgam is removed from the cupped edge 24 of the amalgamating member 21. The amalgamating plates 19 and 23 are also removed and scraped or otherwise treated to remove the amalgam, and resurfaced with mercury when necessary. The sector construction of the plates 19 and 23 facilitates the removal and treatment of the plates, and permits them to be removed and replaced by merely raising the distributing member 27 and the amalgamating member 21 successively from the top of the casing 8 without disconnecting the power connections.

While I have illustrated and described only the preferred embodiment of my invention, the method and machine are of course subject to modification in numerous ways without departing from the spirit of my invention.

I therefore do not wish to restrict myself to the specific form and arrangement or the precise mode of operation disclosed, but desire to avail myself of all modifications which may fall within the scope of the appended claims.

Having thus described my invention what I claim as new and desire to secure by Letters Patent is—

1. An amalgamator comprising a tank having a mercury well and arranged to receive a charge of slimes to be treated; a casing mounted within the tank; a power driven shaft axially disposed within the casing; an impeller adjustably mounted upon the shaft adjacent the bottom of the casing to circulate slimes upwardly through the casing, said impeller being provided with pitched impeller blades operative to lift and hold globules of mercury from the well suspended in the circulating slimes; and means comprising a plurality of downwardly sloping amalgamating plates mounted around the top of the casing for returning slimes overflowing from the casing back into the tank.

2. An amalgamator comprising a tank having a mercury well and arranged to receive a charge of slimes to be treated; a casing mounted within the tank; a power driven shaft axially disposed within the casing; an impeller adjustably mounted upon the shaft adjacent the bottom of the casing to circulate slimes upwardly through the casing, said impeller being provided with pitched impeller blades operative to lift and hold globules of mercury from the well suspended in the circulating slimes; means comprising a plurality of downwardly sloping amalgamating plates mounted around the top of the casing for returning slimes overflowing from the casing back into the tank; and paddles adjustably mounted upon the shaft above the impeller to agitate the slimes and suspended mercury within the casing, and to interrupt the whirling motion of the slimes caused by the impeller.

3. An amalgamator comprising a slime tank having a mercury well and having inlet and outlet openings arranged to permit a charge of slimes to be treated to be introduced and withdrawn from the tank; a casing mounted within the tank; a shaft mounted within the casing; an impeller mounted upon the shaft adjacent the bottom of the casing and arranged to be driven by the shaft to circulate slimes upwardly through the casing, said impeller being arranged to lift and hold globules of mercury from the well suspended in the circulating slimes; means for agitating the slimes and suspended mercury within the casing; an amalgamating member mounted upon the top of the casing; a distributing member mounted above the amalgamating member and apertured to distribute slimes overflowing from the casing even-

ly over said member; and an amalgamating tray mounted upon the top of the tank and arranged to receive slimes from the amalgamating member and return the same to the 5 tank.

4. An amalgamator comprising a slime tank having a mercury well and having inlet and outlet openings arranged to permit a charge of slimes to be treated to be introduced 10 and withdrawn from the tank; a casing mounted within the tank; a shaft mounted within the casing; an impeller adjustably mounted upon the shaft adjacent the bottom of the casing and arranged to be driven by 15 the shaft to circulate slimes upwardly through the casing, said impeller being arranged to lift and hold globules of mercury from the well suspended in the circulating slimes; means adjustably mounted upon the 20 shaft for agitating the slimes and suspended mercury within the casing; an amalgamating member mounted upon the top of the casing; a distributing member mounted above the amalgamating member and apertured to 25 distribute slimes overflowing from the casing evenly over said member; and an amalgamating tray mounted upon the top of the tank and arranged to receive slimes from the amalgamating member and return the same 30 to the tank.

5. In an amalgamator, a tank having a mercury well and arranged to receive a charge of slimes to be treated; a casing mounted within the tank; a power driven shaft axially disposed within the casing; an impeller mounted upon the shaft in spaced relation to the mercury well, said impeller being provided with pitched impeller blades and being axially adjustable along the shaft; and 40 an agitator adjustably mounted upon the shaft between the impeller and the top of the casing, said agitator comprising a hub provided with paddle blades adapted to interrupt the whirling movement of the slimes 45 forced upwardly through the casing by the impeller.

6. In an amalgamator, a tank having a mercury well and arranged to receive a charge of slimes to be treated; a casing vertically disposed within the tank and open at top and bottom; a power actuated impeller mounted within the casing for circulating the slimes upwardly through the casing, said impeller being provided with pitched blades operating to lift globules of mercury from the well and to hold said globules suspended in the upwardly circulating slimes; an amalgamating tray mounted upon the top of the tank, said tray being provided with a flanged bottom seating upon the top of the tank and sloping inwardly from all sides to a central 55 opening around the casing and adapted to return the slimes to said casing; an amalgamating member seated upon the top of the tank and sloping downwardly toward the outer rim of the tray, and having a central 60 opening, said tray and the amalgamating member being provided with amalgamating plates removably mounted upon their upper surfaces; and a distributing member seated upon the top of the amalgamating member and sloping downwardly toward the outer rim of the tray, and having a central 65 opening around the casing and adapted to return the slimes to said casing; an amalgamating member seated upon the top of the tank and sloping downwardly toward the outer rim of the tray, and having a central 70 opening, said tray and the amalgamating member being provided with amalgamating plates removably mounted upon their upper surfaces.

7. In an amalgamator, a tank having a mercury well and arranged to receive a charge of slimes to be treated; a casing vertically disposed within the tank and open at top and bottom; a power actuated impeller mounted within the casing for circulating the slimes upwardly through the casing, said impeller being provided with pitched blades operating to lift globules of mercury from the well and to hold said globules suspended in the upwardly circulating slimes; an amalgamating tray mounted upon the top of the tank, said tray being provided with a flanged bottom seating upon the top of the tank and sloping inwardly from all sides to a central 75 opening around the casing and adapted to return the slimes to said casing; an amalgamating member seated upon the top of the casing and sloping downwardly toward the outer rim of the tray and having a central 80 opening, said tray and the amalgamating member being provided with amalgamating plates removably mounted upon their upper surfaces; and a distributing member seated upon the top of the amalgamating member and sloping downwardly toward the outer rim of the tray and having a central 85 opening, said tray and the amalgamating member being provided with amalgamating plates removably mounted upon their upper surfaces; and a distributing member seated upon the top of the amalgamating member and adapted to distribute the overflow from the casing uniformly over the amalgamating member.

8. In an amalgamator, a tank having a mercury well and arranged to receive a charge of slimes to be treated; a casing vertically disposed within the tank and open at top and bottom; a power actuated impeller mounted within the casing for circulating the slimes upwardly through the casing; an amalgamating tray mounted upon the top of the tank, said tray being provided with a flanged bottom seating upon the top of the tank and sloping inwardly from all sides to a central 90 opening around the casing and adapted to return the slimes to said casing; an amalgamating member seated upon the top of the casing and sloping downwardly toward the outer rim of the tray and having a central 95 opening, said tray and the amalgamating member being provided with amalgamating plates removably mounted upon their upper surfaces; and a distributing member seated upon the top of the amalgamating member and adapted to distribute the overflow from the casing uniformly over the amalgamating member.

9. In an amalgamator, a tank having a

mercury well and arranged to receive a charge of slimes to be treated; a cylindrical casing open at both ends supported within the tank, the lower end of the casing being held in spaced relation to the bottom of the tank and the mercury well therein, and the upper end of the casing being of reduced diameter and extending above the upper edge of the tank; a power driven shaft axially disposed within the casing and extending outwardly through the top thereof; an impeller mounted upon the shaft in spaced relation to the bottom of the tank and casing and provided with pitched impeller blades adapted to circulate slimes upwardly through the casing; an amalgamating tray seated upon the top of the tank and having a central opening through which the casing projects upwardly, said tray sloping from all sides to the central opening to return slimes to the casing, and being provided with a plurality of segmental amalgamating plates lining the bottom thereof; and an amalgamating member seated upon the reduced upper end of the casing and having a central opening matching with the open top of said casing, said member sloping outwardly toward the outer edge of the tray and provided with a plurality of segmental amalgamating plates surfacing the upper face thereof.

10. In an amalgamator, a tank having a mercury well and arranged to receive a charge of slimes to be treated; a cylindrical casing open at both ends supported within the tank, the lower end of the casing being held in spaced relation to the bottom of the tank and the mercury well therein, and the upper end of the casing being of reduced diameter and extending above the upper edge of the tank; a power driven shaft axially disposed within the casing and extending outwardly through the top thereof; an impeller mounted upon the shaft in spaced relation to the bottom of the tank and casing and provided with pitched impeller blades adapted to circulate slimes upwardly through the casing, said impeller being provided with pitched blades operating to lift globules of mercury from the well and to hold said globules suspended in the upwardly circulating slimes; an amalgamating tray seated upon the top of the tank and having a central opening through which the casing projects upwardly, said tray sloping from all sides to the central opening to return slimes to the casing, and being provided with a plurality of segmental amalgamating plates lining the bottom thereof; and an amalgamating member seated upon the reduced upper end of the casing and having a central opening matching with the open top of said casing, said member sloping outwardly toward the outer edge of the tray and provided with a plurality of segmental amalgamating plates surfacing the upper face thereof; and a dis-

tributing member seated upon the top of the amalgamating member and adapted to distribute slimes circulated upwardly through the casing uniformly over the amalgamating member. 70

11. In an amalgamator, the combination with a tank having a mercury well in the bottom thereof and arranged to receive a charge of slimes to be treated, of a casing mounted within the tank and having its lower end opening above the well; and a power driven impeller mounted within the bottom of the casing and spaced above the well, said impeller being provided with pitched blades operating to circulate the slimes upwardly through the casing and to lift globules of mercury from the well by suction and to hold said globules suspended in the upwardly circulating slimes.

12. In an amalgamator, the combination 85
with a tank having a mercury well in the bottom thereof and arranged to receive a charge of slimes to be treated, of a casing mounted within the tank and having its lower end opening above the well; a power driven impeller 90
mounted within the bottom of the casing and spaced above the well, said impeller being provided with pitched blades operating to circulate the slimes upwardly through the casing and to lift globules of mercury from the well by suction and to hold said globules suspended in the upwardly circulating slimes; and means for adjusting the impeller axially within the casing to vary the lifting force of said impeller upon mercury within 95
the well. 100

13. In an amalgamator, the combination with a tank having a mercury well in the bottom thereof and arranged to receive a charge of slimes to be treated, of a casing mounted within the tank and having its lower end opening above the well; a power driven impeller mounted within the bottom of the casing and spaced above the well, said impeller being provided with pitched blades operating to circulate the slimes upwardly through the casing and to lift globules of mercury from the well by suction and to hold said globules suspended in the upwardly circulating slimes; and paddles mounted within the casing in spaced relation to the impeller, and actuated in common with said impeller to interrupt the whirling action of the slimes within the casing.

14. In an amalgamator, the combination 120
with a tank having a mercury well in the bot-
tom thereof and arranged to receive a charge
of slimes to be treated, of a casing mounted
within the tank and having its lower end
opening above the well; a power driven im- 125
peller mounted within the bottom of the
casing and spaced above the well, said impel-
ler being provided with pitched blades op-
erating to circulate the slimes upwardly
through the casing and to life globules of 130

mercury from the well by suction and to hold said globules suspended in the upwardly circulating slimes; means for adjusting the impeller axially within the casing to vary the lifting force of said impeller upon mercury within the well; and paddles mounted within the casing in spaced relation to the impeller and actuated in common with said impeller to break up the whirling action of the slimes

5 within the casing.

10 15. In an amalgamator, the combination with a tank having a mercury well in the bottom thereof and arranged to receive a charge of slimes to be treated, of a casing mounted within the tank and having its lower end opening above the well; a power driven impeller mounted within the bottom of the casing and spaced above the well, said impeller being provided with pitched blades operating

20 to circulate the slimes upwardly through the casing and to lift globules of mercury from the well by suction and to hold said globules suspended in the upwardly circulating slimes; means for adjusting the impeller axially within the casing to vary the lifting force of said impeller upon mercury within the well; paddles mounted within the casing in spaced relation to the impeller and actuated in common with said impeller to break up

25 the whirling action of the slimes within the casing; and means for adjusting the paddles axially within the casing to vary the spacing of said paddles above the impeller.

30 In witness whereof, I hereunto set my signature.
